ELECTRONIC TONAL STETHOSCOPE

Winslow B. M. Clark, Van Nuys, and Wallace R. Spark,
Venice, Calif., assignors to Douglas Aircraft Company,
Inc., Santa Monica, Calif.

Filed Oct. 11, 1962, Ser. No. 72,067

Term of patent 14 years

(Cl. D83—12)

FIGURE 1 is a perspective view taken from the top and rear of an electronic tonal stethoscope embodying our new design, with a pair of ear pieces shown in broken lines for illustrative purposes only;

FIGURE 2 is a top plan view thereof;

FIGURE 3 is a side elevational view thereof;

FIGURE 4 is a front elevational view thereof; and

FIGURE 5 is a rear elevational view thereof.

The other side, not shown, of the electronic tonal stethoscope is similar to the side which is illustrated, and the bottom, not shown, is substantially plain.

The dominant features of our design reside in the portions shown in full lines.

We claim:

The ornamental design for an electronic tonal stethoscope, substantially as shown and described.
